UNITED STATES PATENT OFFICE.

ARTHUR C. JACKSON, OF PHILADELPHIA, PENNSYLVANIA, AND WALDEMAR KROLL, OF SAN FRANCISCO, CALIFORNIA, ASSIGNEES TO THE YALE & TOWNE MANUFACTURING COMPANY, OF STAMFORD, CONNECTICUT, A CORPORATION OF CONNECTICUT.

PADLOCK.

Application filed March 17, 1926. Serial No. 95,308.

Our invention relates to certain improvements in padlocks, particularly of the type in which a U-shaped shackle is adjustably mounted in the lock casing, but it will be understood that the invention can be applied to other types of padlocks without departing from the essential features of the invention.

One object of our invention is to so design the lock that the mechanism of the same can be assembled between two plates which are inserted in a lock casing having a cover plate which encloses the mechanism.

Another object of the invention is to provide a struck-up sheet-metal casing for the lock mechanism which can be cheaply and accurately manufactured.

A further object of the invention is to so design the several plates of the lock that when the lock is assembled the several parts will be in proper alignment.

A still further object of the invention is to so construct the bolt that when it is in engagement with one of the ratchet-teeth of the shackle, any pulling strain on the shackle will be taken by the casing through the guiding and spacing member.

And a still further object of the invention is to so design the lock that the bolt will interfere with the insertion of the shackle when applied to the lock in the reverse direction.

Other objects and details of construction and operation will be hereinafter fully described.

In the accompanying drawings:

Fig. 1 is a face view of our improved padlock;

Fig. 2 is an enlarged sectional view on the line 2—2, Fig. 5;

Fig. 3 is a sectional view on the line 3—3, Fig. 5;

Fig. 4 is a sectional view similar to Fig. 3, with the tumblers removed;

Fig. 5 is a sectional view on the line 5—5, Fig. 3;

Fig. 6 is a sectional view on the line 6—6, Fig. 3;

Fig. 7 is a detached sectional view showing the casing, cover plate, works-carrying plates, and spacing member;

Fig. 8 is a detached perspective view of the guide and spacing member;

Fig. 9 is a detached perspective view of the bolt;

Fig. 10 is a view of the stop plate of the key; and

Fig. 11 is a view illustrating a modification of the casing and works-carrying plates.

Referring to the drawings, the casing of the lock is cylindrical in the present instance, and has a shouldered portion 2, on which 60 rests the cover plate 3 of the lock when the edge 4 of the casing is turned over it, as clearly shown in Fig. 5.

Between the back of the casing and the cover plate is a works-carrying frame, consisting of a rear plate 5, a front plate 6, and a guiding and spacing member 7. This member is clearly shown in Fig. 8. The spacing member has lugs 8 which extend through openings 9 in the two plates 5 and 6, and these 70 lugs may be riveted onto the plates if desired after the locking mechanism is assembled between the plates.

Secured to the two plates 5 and 6 are posts 10—10, between which are located wards 11 and spacing washers 12, said wards being shaped to receive the key. In alignment with the wards is a key-plate 13, in the form of a flanged disk and slotted to receive the key. The flange of the key-plate extends between 80 the outer works-carrying plate and the cover plate 3, as clearly shown in Fig. 5.

14 is a pivot post for the bolt 15, which is shaped as shown in Fig. 9, and has a right angular extension 16, which is arranged to 85 engage one of the ratchet-teeth 17 on the U-shaped shackle 18. The guide and spacing member is U-shaped as clearly shown in Fig. 8, having two parallel guiding members 19 and 19^a and a connecting member 20, which latter fits against the upper surface of the lock casing (see Fig. 3). The guiding members 19 and 19^a are flanged as shown at 21, and resting on the flanges are the works-carrying plates 5 and 6. The lugs 8 project 95 from these flanges through the openings, as previously described.

The guiding and spacing member 7 is notched at 22 for the passage of an extension 16 of the bolt, so as to allow it to engage one 100 of the ratchet-teeth 17 of the shackle, as clearly shown in Figs. 3 and 4. It will be

noted that in referring to Fig. 3 the lower edge of the extension of the bolt rests upon the upper edge of one of the ratchet-teeth, while the upper edge of the bolt rests against 5 the wall of the notch 22 in the guiding and spacing member. By this construction the delicate locking mechanism is relieved from strain in the case of any pull upon the shackle, as the strain is taken by the guiding and 10 spacing member 7 and transmitted to the casing of the lock.

23 is a post secured to the two plates 5 and 6, and mounted on the post is a flared U-shaped spring 24. One arm of the spring 15 bears against the guiding member 19^a, while the other end of the spring rests against the extension 16 of the bolt 15, and tends to force the bolt into engagement with the shackle. The bolt 15 has a projecting portion 25 in 20 the path of the key, so that when the key is turned in the lock it will bear upon the projection 25 and turn the bolt on its pivot and release the shackle.

At the bottom of the lock is a stop plate 26, 25 which is cut away to allow the key to turn a quarter of a revolution and strike the shoulder 27 on the plate. This plate is held between the posts 10—10 and the bottom flange of the guide member 19. This flange is 30 notched at 28 to receive a projection 29 on the plate 26, so that the plate is firmly held between the guiding member 19 and the posts 10. This plate is preferably the same height as the bolt, so as to form with the bolt a 35 port for the wards and washers. On the pile of wards is a spring-washer 30, which bears against the upper works-carrying plate 6 and tends to hold the wards and washers in position.

40 In order to insure proper alignment of the several parts of the lock, the inner wall of the casing has a groove 31, and each works-carrying plate 5 and 6 has a lug 32 extending into the groove 31, so that when the mechanism is 45 assembled the works are brought into proper alignment with the openings 33 in the lock casing for the shackle. As these openings must be in alignment with the guiding members 19 and 19^a, and in order to insure the 50 cover plate 3 being in alignment with the other parts of the lock, the upper works-carrying plate is notched as at 34 to receive a lug 35, Fig. 2, bent from the cover plate 3.

By the above arrangement, it will be seen 55 that the mechanism of the lock can be assembled between the two works-carrying plates and then inserted bodily in the casing. The parts are brought into proper alignment, an accurate fit is assured, and the assembling 60 of the lock is made a simple matter.

By making the several parts register, the name or other marks on the cover plate are 65 brought into proper position in respect to the name or other matter at the rear of the casing, and by so proportioning the extension 16

of the bolt that it fits between one of the teeth of the shackle and the upper surface of the notch in the guide member 19, any strain caused by an excessive pull on the shackle will be taken by the casing through the guide. 75

Furthermore, the extension 16 of the bolt projects sufficiently into the guide-way for the shackle that the latter cannot be introduced into the lock casing in the reverse direction. This is an important feature in locks of this 75 type.

By constructing the lock in the manner shown, a very narrow shackle can be used, and as both arms of the shackle are provided with 80 teeth, either arm of the shackle can be introduced into the notched guide, but it will be understood that the bolt only engages one arm of the shackle.

In the main figures of the drawings a single 85 shell, which forms a casing, is shown, whereas in Fig. 11 is shown a double shell. The plate 6^a has a deep flange 6^b in which the lock mechanism is located, and the plate 5^a is secured to the plate 6^a by the guiding and spacing member 7. The outer shell which forms the casing is made with a deep flange as at 1^a, and the cover plate 3^a is secured to the casing in the same manner by beading over the edge of the flange of the shell 1^a. Thus in this 90 instance the edge of the lock structure when 95 assembled is doubled.

We claim:—

1. The combination of a casing having an integral back section and a deep flange, the flange of said section having a groove in its inner face; works-carrying plates mounted within the casing and the plates having lugs extending into the groove; a guide and spacing member located between the two works-carrying plates, the casing being perforated in alignment with the guides; a U-shaped shackle arranged to pass through the perforations, one of the arms of said shackle having teeth, a bolt arranged to engage the toothed shackle; and a cover plate having a tongue, 105 and the works-carrying plates adjacent the cover having a notch to receive the tongue whereby the several parts are brought into alignment. 110

2. The combination of an outer casing, 115 and a cover plate therefor; an inner and an outer works-carrying plate mounted in the casing; a guide and spacing member consisting of two parallel members and a connecting yoke, said guide and spacing member being located between the two works-carrying plates, the casing being perforated in alignment with the guide and spacing member; a shackle extending through perforations in the casing; and a bolt arranged to engage one 120 arm of the shackle. 125

3. The combination of a casing; works-carrying plates; a guide and spacing member located between the plates, the casing being perforated in alignment with the guide- 130

ways of the guide and spacing member; a shackle arranged to extend through the perforations in the casing, the guide and spacing member being notched; and a bolt located in 5 the space between the works-carrying plates and having a portion arranged to extend into the notch in the guide and spacing member and engage the shackle.

4. The combination of a casing; works-carrying plates; a guide and spacing member located between the plates, the casing being perforated in alignment with the guideways of the guide and spacing member; a toothed shackle arranged to extend through the perforations in the casing, the guide and spacing member being notched; and a bolt located in 10 the space between the works-carrying plates and having a projecting portion arranged to enter the notch in the guide and spacing member and to engage the toothed shackle, one 15 side of the projecting portion being in alignment with the shackle, and the other end engaging the wall of the notch in the guide and spacing member, so that any pull on the 20 shackle will be directly against said member.

5. The combination of a casing having an integral back and a deep flange, said flange having a shoulder; a cover plate resting on the shoulder, the flange being turned over the 25 cover plate; two works-carrying plates mounted within the casing; a guide and spacing member located between the two plates and having lugs, the plates having perforations to receive the lugs; guide posts extending from 30 one plate to the other; wards and washers located between the posts and within the guide and spacing member; a toothed shackle; a bolt pivoted to the works structure and having a portion arranged to engage a tooth of the 35 shackle; a spring tending to hold the bolt in engagement with the shackle; a stop plate in the same plane as the bolt, said stop plate having a projection, the guide and spacing member being recessed to receive the projection, and the guide and spacing member also 40 being notched to receive the end of the bolt.

6. A guide and spacing member for a padlock made in one piece and consisting of, two parallel sections connected by an integral 45 yoke, each section forming a guide for a leg of a shackle of a padlock, and one of said sections being notched to receive a bolt.

7. A guide and spacing member for a padlock made in one piece and U-shaped in form

to provide two parallel guiding sections, each 55 section of the guide and spacing member having an open passage for a shackle, and having lugs arranged to extend into perforations in carrying-plates.

8. The combination in a padlock, of a casing having openings at opposite sides for the passage of a shackle; a cover plate for the casing; works-carrying plates, a spacing guide for a U-shaped shackle, said guide having a 60 notch; a toothed U-shaped shackle extending through the openings in the casing; a bolt; and a spring arranged to hold the bolt normally within the notch of the guide, said bolt preventing the passage of the shackle in the 65 wrong direction.

9. The combination in a padlock, of a casing; a cover plate therefor; front and back works-carrying plates; a combined U-shaped spacing and guiding member located between the two works-carrying plates and attached 70 thereto; a toothed U-shaped shackle arranged to slide in the casing and against the sides of the guiding member; a bolt arranged to engage one arm of the shackle; and locking mechanism located in the space between the 75 two works-carrying plates and between the two arms of the spacing and guiding member.

10. The combination in a padlock, of a casing; a cover plate therefor; front and back works-carrying plates; a combined U-shaped spacing and guiding member located between the two works-carrying plates; guide ways 80 in each side of the spacing and guiding member, the casing being perforated in line with the guide ways; a toothed U-shaped shackle 85 extending through the perforations in the casing and in each guide way; posts secured to the works-carrying plates; and a bolt mounted on a pivot and arranged to engage one of the toothed arms of the shackle.

11. The combination in a padlock, of a casing having a deep flange, the flange having a deep groove in its inner wall; a works-carrier consisting of two plates and a spacing member, said carrier having a lug extending into 90 the groove in the flange of the casing, the outer works-carrying plate having a notch; and a cover plate having a tongue extending into the notch whereby the several parts are 95 brought into alignment.
